PORTABLE BARBECUE GRILL

Stanley M. Joseph, Burbank, Calif.

Application February 11, 1958, Serial No. 49,590

Term of patent 14 years

(Cl. D81—10)

FIG. 2.

Fig. 1 is a perspective view of the top, front and one side of a portable barbecue grill showing my new design; and

Fig. 2 is a perspective view of the top, rear and other side thereof.

I claim:

The ornamental design for a portable barbecue grill, substantially as shown.
